UNITED STATES PATENT OFFICE.

WILLIAM F. SCHILLING, OF OSHKOSH, WISCONSIN.

CLOTHES-HANGING DEVICE.

Application filed January 26, 1923. Serial No. 615,087.

To all whom it may concern:

Be it known that I, WILLIAM F. SCHILLING, a citizen of the United States, residing at Oshkosh, in the county of Winnebago and 5 State of Wisconsin, have invented certain new and useful Improvements in a Clothes-Hanging Device, of which the following is a specification.

The present invention relates to a clothes 10 hanging device and has for its principal object to provide a simple and efficient structure of this nature which will be reliable in operation, inexpensive to manufacture, durable, and well adapted for the purpose for 15 which it is designed.

Another object of the invention is to provide a hanging device of this nature which is useful in supporting shirts and other like garments upon a clothes line so that the 20 garment may dry in a substantially unruffled condition.

Another important object of the invention is to provide a hanging device of this nature with means for engaging a garment 25 and similar means for engaging a support such as a clothes line, said means being arranged so that they will not interfere with each other.

With the above and numerous other objects in view as will appear as the description progresses, the invention resides in certain novel features of construction, and the combination and arrangement of parts as 30 will be hereinafter more fully described and 35 claimed.

In the drawing—

Figure 1 is a perspective view of a plurality of the hanging devices, showing the same as used,

40 Figure 2 is a perspective of one of the hanging devices,

Figure 3 is a side elevation of one of the clips used in conjunction with the hanging devices, and

Figure 4 is a detail perspective of the spring used with the clip.

Referring to the drawing in detail it will be seen that the hanging device consists of a bar 1 having at its ends depending extensions 50 2 which terminate in offset extensions 3 that extend in opposite directions from each other and parallel to the bar 1. Upon the bar 1 there is disposed a plurality of engaging clips 4 of any desired construction and these clips are mounted so as to be adjustable longitudinally of the bar 1. In the il-

lustration shown in Figure 1 these clips 4 are adapted to engage the clothes line. On the offset extensions 3 which are disposed beyond the ends of the bar 1 there are situated the clips 5 which are preferably the same construction as the clips 4. The clips 5 are mounted on the extension 3 so that they may be adjusted longitudinally that is so that they may be moved toward or away from 65 each other for attachment to garments of various widths.

I have shown the detail structure of the clips in Figures 3 and 4. Each clip 5 includes members 11 and 10, the latter of which is 70 provided with a projection 12 intermediate its ends seated in the depression 13 of the first member whereby the members are rockably associated with each other. The spring 14 has its intermediate portion passing 75 through the two members 10 and 11 and the terminals of its arms engaging the members a distance from the location of the projection 12 so as to hold the clips in a closed position normally. The projection 12 is provided with an opening through which extends the bar 1 so that the clip is capable of sliding thereon. There are numerous clips now on the market which may be used 80 in place of the structure which I have just 85 described and no claim is made to the particular clip described except as may be hereinafter claimed in combination with the bar 1.

Although I have described my invention 90 with some degree of particularity it is to be understood that numerous changes in the details of construction and in the combination and arrangement of parts may be resorted to without departing from the spirit 95 of the invention as hereinafter claimed.

Having thus described my invention what I claim as new is:—

1. A device of the class described including a bar having depending extensions at its ends, offset extensions disposed on the depending extensions and situated in parallelism with the bar and beyond the ends thereof, a plurality of clips on the bar and a clip on each offset extension, said clips being longitudinally adjustable.

2. A device of the class described including a bar, extensions formed on the ends of the bar out of alignment therewith and beyond the ends thereof, a clip on the bar, and a clip on each of the extensions, said clips being longitudinally adjustable.

3. A device of the class described including an elongated bar, right angular extensions on the ends of the bar, second right angular extensions on the ends of the first extensions and disposed in parallelism with the bar and beyond the ends thereof, a pair of clips disposed on the bar and movable longitudinally thereon and adapted to be engaged with a support such as a clothes line, and a clip disposed on each of the last

mentioned extensions and movable longitudinally thereon and adapted to engage with a garment or the like.

In testimony whereof I affix my signature in presence of two witnesses.

WILLIAM F. SCHILLING.
